COIN BANK

Charles M. Dale, Scarsdale, N. Y., assignor to The
Coinmaster Corp., a corporation of New York

Application July 2, 1945, Serial No. 602,766

10 Claims. (Cl. 232—4)

1

This invention relates to coin banks, particularly of the type capable of being opened only when the bank or a portion thereof is full.

Most banks in this category are adapted to house a single column of coins, and where provision is made for more than one column, separate opening mechanisms are generally required for each column. It is within the contemplation of my invention to provide a bank of this class adapted to house several columns of coins, yet containing a unitary manually manipulable mechanism for opening the bank when either one or more of the column compartments are full.

It is a further object of this invention to provide a device of the above-mentioned class of attractive and presentable appearance, and wherein the very features that give the device its aesthetic value serve also certain important mechanical functions. And in this aspect of my invention it is an important object to enable the ornamental design features to perform, among others, two valuable functions—to conceal the manually manipulable mechanism, and to hold against rotation a movable coin-supporting platform constituting an important element of my invention, the non-rotatability of said platform being operatively desirable.

It is also an object of this invention to provide the coin housing with means for preventing the coins of one column from being inadvertently displaced into an adjacent coin compartment.

And it is within my contemplation to attain the aforesaid objectives by means of a compact, easily fabricated and inexpensive device.

Other objects, features and advantages will appear from the drawings and the description hereinafter given.

Referring to the drawings,

Figure 1 is a perspective view of a preferred form of coin bank according to this invention.

Figure 2 is a vertical section of Figure 1 taken substantially along line 2—2 thereof.

Figure 3 is a section of Figure 2 taken along line 3—3 thereof.

Figure 4 is a section of Figure 2 taken along line 4—4 thereof.

Figure 5 is a fragmentary section of Figure 2 taken along line 5—5 thereof.

Figure 6 is vertical section, substantially like Figure 2, showing a column of coins operatively pushing open the cover.

Figure 7 is a perspective view of the central partition member, and

2

Figure 8 is a perspective view of the spring coin stop interposed adjacent the coin slot.

In the particular embodiment of my invention illustrated in the drawings, the coin bank 5 comprises a hollow base member 10 upon which is supported the coin housing 11. The method of attachment is through the prong members 12 extending through suitable slits in the base and bent against the underside thereof—although 10 any other known method of attachment may be employed within the scope and intent of this invention. The said housing consists of three compartments 13, 14 and 15, the outer walls of each being of arcuate cross-section joined together at 15 vertical junctures 16, 17 and 18. These junctures constitute recessed portions of the entire housing 11, and produce a clover-leaf appearance when viewed from the top. As will hereinafter appear, this arrangement not only serves an 20 aesthetic purpose, but also has an important utilitarian function.

The three coin compartments are provided with coin slots 19, 20 and 21 near the top thereof. The entire housing is provided with a cover member 22 which is arranged to be inserted within the upper portion of the housing and frictionally engageable with the wall thereof. In the particular embodiment shown, the upper wall of the housing is provided with a peripherally disposed recess 23, and the lateral wall 24 of the cover member is provided with a similarly arranged recess 25 shaped and proportioned so that it will enter and be in frictional engagement with the recessed portion 23. The said recessed 30 portions 23 and 24 may be in the nature of bumps adapted for mutual coactive frictional engagement, so that when the cover member 22 is in position within the housing as illustrated, it will be frictionally held in place and adapted for removal only by an upward push from within. It is preferred that the uppermost edge 26 of the housing be substantially flush with the top wall 27 of the cover, so that said cover could not be conveniently grasped for removal from without. 40 It is obvious that the said cover 22 is also of clover-leaf construction so as to conform to the shape of the housing. The proportions of the compartments 13, 14 and 15 can be made to accommodate predetermined denominations of 45 coins, such as dimes for compartment 13, nickels for compartment 14 and quarters for compartment 15. 50 The cover member 22 is also provided on the underside thereof with three spring members 28 at the upper portions of the compartments,

said spring members extending to the level of the coin slots so as to constitute an obstruction to the removal or inadvertent slipping out of the coins through said slots. The spring members, however, are curved upwardly, so as to yieldably permit the insertion of coins through the slots. In the particular form shown, each of the spring members 28 extends downwardly from an anchorage 29 suitably secured to the underside of cover 22.

The bottom of the housing is provided with a vertically movable platform 30 shaped to conform to the clover-like cross-sectional area of the three compartments and proportioned so as to extend substantially across all of said compartments whereby the platform could operatively support coin columns in each of the compartments. The platform contains a downwardly extending boss 31 and a central threaded hole 32 in operative engagement with the threaded shank 33 of the screw member 34. Said screw-member contains a head portion 35 disposed within the hollow of base 10 and resting flush against the horizontal underside 36 of the base, the said shank extending upwardly through hole 37 in the base and to a point above the lowermost position of the platform—the length of the shank extending thereabove being sufficient to permit an operative movement of the platform upwardly a predetermined distance—sufficient to enable it to effectuate its cover-removing function, in a manner to be hereinafter described. Suitably affixed to shank 33 is the disk 38 which overlies the upper horizontal surface of the base, said disk 38 and head 35 preventing any vertical movement of the screw, although not preventing its operative rotation. The arrangement is such that upon a turning of the screw, the platform 30 can be made to move up or down, depending upon the direction of rotation.

Centrally disposed within the housing is the separator or partition member 39 consisting, in the particular form illustrated, of three vertically disposed concave walls 40, 41 and 42 complementary to compartments 13, 14 and 15, respectively. Said separator may extend up to the top of the housing, the lower portion containing the legs 43, 44 and 45 extending through corresponding holes 46, 47 and 48 in the platform 30 and being anchored to the top of base 10 either by rivets or in any other known manner. The legs 43, 44 and 45 are of such length as to permit an upward movement of the platform 30, the length of the legs corresponding approximately to the predetermined vertical operative movement of the platform 30.

In the operation of this device the platform 30 is set into its lowermost position and the cover 22 is placed in its operatively closed position as is illustrated in Figure 5. As coins are inserted in the various slots 19, 20 and 21, they will fall to the platform 30, within their respective compartments, forming columns of coins as they are being deposited. The partition member 39, extending vertically upwardly, constitutes the inner portions of the three compartments and serves the purpose of preventing coins from one compartment from inadvertently falling into another—thereby maintaining the three columns of coins in their proper operative positions for coactive use with the platform, as will be herein-after set forth. When any of the coin compartments are filled with coins—or if desired, when all of the compartments are so filled—the device can be manipulated so as to cause an opening of

the cover 22 and a removal of the coins. When this condition occurs, as indicated in Figure 6, all that need be done is to rotate the screw member 35 in a clockwise direction. This will cause the platform to rise, thereby pushing the one or more filled coin columns against the underside of cover member 22 to force it open against the frictional grasp of the wall of the housing. It is thus obvious that only when a column of coins reaches a predetermined upper level that the bank can be opened. This construction constitutes a salable feature, inasmuch as there is an inducement to save, or at least to fill the bank before it can be opened.

It is important to note that the recessed portions 16, 17 and 18 of the housing which, as aforesaid, serve to enhance the appearance of the device, serve also the important function of preventing the platform 30 from turning. The said platform is, as clearly indicated from the drawings, similar in cross-section to the housing, the indentures 49, 50 and 51 corresponding to said indentures 16, 17 and 18. Hence, should there be any tendency of the platform to turn during an operative manipulation of the screw 34, such turning would be prevented by the walls of the housing.

It is understood that the embodiment above described and shown in the drawings is merely illustrative of my invention, and that numerous changes and modifications may be made therein within the scope of the appended claims without departing from the spirit of this invention.

I claim:

35 1. In a coin bank, a housing having a coin slot near the top, a cover frictionally secured to the top of the housing, a spring pressed guard carried by the cover of the housing and extending in the plane of the slot, a vertically movable platform within the bottom portion of the housing and adapted to support at least one column of coins, and manually manipulable screw means to move the platform vertically within the housing, whereby a column of coins operatively supported by the platform will engage the underside of said guard and force the cover out of its engagement with the housing when the platform is operatively moved upwardly, said housing having a skirt surrounding and laterally concealing said screw means.

40 2. In a coin bank, a housing having a coin slot near the top, a cover in frictional engagement with the wall of the upper portion of the housing at the inner surface thereof, said wall extending substantially to the level of the adjacent uppermost portion of the cover and completely surrounding same, a spring pressed guard carried by the cover of the housing and extending in the plane of the slot, a vertically movable platform within the bottom portion of the housing and adapted to support at least one column of coins, and manually manipulable means to move the platform vertically within the housing, whereby a column of coins operatively supported by the platform will engage the underside of said guard and force the cover out of its engagement with the housing when the platform is operatively moved upwardly.

45 3. In a coin bank, a housing having a coin slot near the top, a base supporting the housing, a cover frictionally secured to the top of the housing, a spring pressed guard carried by the cover of the housing and extending in the plane of the slot, a vertically movable platform within the bottom portion of the housing and adapted

to support at least one column of coins, and screw means supported by the base and in threaded engagement with the platform for vertically moving the platform within the housing, whereby a column of coins operatively supported by the platform will engage the underside of said guard and force the cover out of its engagement with the housing when the platform is operatively moved upwardly, said housing having a skirt surrounding and laterally concealing said screw means.

4. A coin bank comprising a housing having a body for containing coins, a base having a depending skirt secured to and extending below the lower end of the body, a top piece having a frictional connection inside of the upper end of the body, said body having a coin slot beneath the edge of the top piece and a spring pressed guard carried by the top piece and projecting into the plane of the slot at the inner edge thereof and biased to move transversely of the slot and free from contact with the body of the housing and a manually operable compression screw means movable in the base toward and from the top piece for compressing a stack of coins within the housing against the spring pressed guard at the top and forcing the top piece out of the body, said screw means being accessible only within the skirt of the base.

5. In a coin bank, a housing having a coin slot near the top, a hollow base supporting the housing and comprising a horizontal supporting wall and a peripheral wall extending downwardly therefrom, a cover frictionally secured to the top of the housing, a spring pressed guard carried by the cover of the housing and extending in the plane of the slot, a vertically movable platform within the bottom portion of the housing and adapted to support at least one column of coins, said platform in its lowermost position being adapted to be supported by said horizontal wall of the base, and screw means supported by the base and in threaded engagement with the platform for vertically moving the platform within the housing, whereby a column of coins operatively supported by the platform will engage the underside of said guard and force the cover out of its engagement with the housing when the platform is operatively moved upwardly, said screw means comprising a head portion within the hollow portion of the base and in engagement with the underside of the said horizontal wall thereof, a shank in threaded engagement with the platform and extending upwardly a sufficient distance to permit a predetermined operative movement of the platform, and a collar affixed to the shank and in engagement with the upper surface of the said horizontal wall of the base.

6. In a coin bank, a housing with a plurality of vertical indentures extending substantially along the length thereof, a cover frictionally secured to the top of the housing, a vertically movable platform within the bottom portion of the housing and containing indentures to correspond with the indentures of the housing, the platform being proportioned to substantially correspond with the size and shape of the cross-sectional area of the interior of the housing, whereby the platform could move vertically but will be held against rotation by the indentures of the housing, the platform being adapted to support at least one column of coins, said housing having a coin slot near the top, a spring pressed guard carried by the cover and extending in the plane of the slot, and manually ma-

nipulable means to move the platform vertically within the housing, whereby a column of coins operatively supported by the platform will engage the underside of said guard and force the cover out of its engagement with the housing when the platform is operatively moved upwardly.

7. In a coin bank, a housing having a plurality of vertical compartments each being adapted to accommodate a column of coins and having 10 a coin slot near the top of each compartment, a cover frictionally secured to the top of the housing, a spring pressed guard projecting from the cover into the plane of each slot, a vertical partition member within the housing and disposed 15 substantially at the innermost portions of said compartments, whereby the compartments are operatively separated from one another, a vertically movable platform within the bottom portion of the housing and extending into each of 20 said compartments, the platform being adapted to support a column of coins in each compartment, and manually manipulable means to move the platform vertically within the housing, whereby one or more columns of coins operatively supported by the platform will engage the 25 underside of said guards and force the cover out of its engagement with the housing when the platform is operatively moved upwardly.

8. In a coin bank, a housing having a plurality of vertical compartments each being adapted to accommodate a column of coins and having 30 a coin slot near the top of each compartment, a cover frictionally secured to the top of the housing, a spring pressed guard projecting from the cover into the plane of each slot, a vertical partition member within the housing and disposed 35 substantially at the innermost portions of said compartments, whereby the compartments are operatively separated from one another, a base supporting said housing, said partition member containing at the lower portion thereof a plurality of legs supported by said base, a vertically movable platform within the bottom portion of the housing and extending into each of 40 said compartments, the platform being adapted to support a column of coins in each compartment, said platform containing a plurality of apertures therein spaced and proportioned to accommodate therein the legs of said partition member, and manually manipulable means to 45 move the platform vertically within the housing, whereby one or more columns of coins operatively supported by the platform will engage the underside of said guards and force the cover out 50 of its engagement with the housing when the platform is operatively moved upwardly.

9. In a coin bank, a housing, a base supporting the housing, the lateral wall of the housing containing a plurality of arcuate sections joined 60 at vertically extending indentures, thereby forming a plurality of vertical coin compartments, each compartment having a coin slot near the top, a cover frictionally secured to the top of the housing and disposed over all of said compartments, spring pressed guards carried by the cover and extending into the plane of the slots, a vertical partition member consisting of a plurality of adjacent vertical concave walls forming the inner walls of the compartments, a base supporting the said housing, said partition member containing at the lower portion thereof a plurality of legs supported by said base, a vertically movable platform within the bottom portion of the housing and extending into each of said compartments, the platform being adapted to sup- 65 70 75

port a column of coins in each compartment, said platform containing a plurality of apertures therein spaced and proportioned to accommodate therein the legs of said partition member, and manually manipulable means to move the platform vertically within the housing, whereby one or more columns of coins operatively supported by the platform will engage the underside of said spring pressed guards and force the cover out of its engagement with the housing when the platform is operatively moved upwardly.

10. In a coin bank, a housing of substantially clover-leaf cross-sectional configuration, whereby three vertical compartments are formed, each compartment having a coin slot near the top thereof, a base supporting the housing, a cover shaped to correspond with the housing and frictionally secured to the top wall thereof, spring pressed guards carried by the cover and extending into the plane of the slots, a vertical partition member within the housing and disposed substantially at the innermost portions of said compartments, whereby the compartments are operatively separated from one another, said partition member consisting of a plurality of adjacent vertical concave walls extending vertically substantially the height of the housing and forming the inner walls of the compartments, said partition member containing at the lower portion thereof a plurality of legs supported by said base, a vertically movable platform within the bottom portion of the housing and extending into each of said compartments, the platform being adapted

5 to support a column of coins in each compartment, means to hold the platform against rotation, said platform containing a plurality of apertures therein spaced and proportioned to accommodate therein the legs of said partition member, and screw means supported by the base and in threaded engagement with the platform for vertically moving the platform within the housing, whereby one or more columns of coins operatively supported by the platform will engage the underside of said guards and force the cover out of its engagement with the housing when the platform is operatively moved upwardly.
